Primary Examiner — Sheryl Lane*Assistant Examiner* — Mark T. Philippss(74) *Attorney, Agent, or Firm* — Taylor J. Ross(57) **CLAIM**

The ornamental design for a water pump, as shown and described.

DESCRIPTION

This application is related to co-pending Ser. No. 16/534, 043, filed Aug. 7, 2019, which is incorporated herein by reference.

FIG. 1 is a top, front and left side isometric view of a water pump showing my new design;

FIG. 2 is a bottom, rear and left side isometric view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The broken lines represent portions of the water pump and form no part of the claimed design. The alternating long dash short dash lines define the bounds of the claim and form no part of the claimed design.

1 Claim, 5 Drawing Sheets(56)
